PRODUCTION OF SYNTHETIC THREADS

Glen S. Hiers, Bala-Cynwyd, Pa., assignor to
 Collins & Aikman Corporation, Philadelphia,
 Pa., a corporation of Delaware

Application June 6, 1934, Serial No. 729,251

6 Claims. (Cl. 18—54)

This invention relates to methods of and apparatus for producing synthetic threads from viscous solutions such as aqueous dispersions of latex or compositions thereof; artificial dispersions of 5 claimed or of crude rubber; dispersions of rubber in organic solvents; cupra-ammonium cellulose; cellulose acetate; nitro-cellulose; etc.

Ordinarily, synthetic threads are formed from these various emulsions or solutions by expulsion 10 or extrusion through nozzle orifices, and by subsequent treatment of the resulting filaments either with heat or by subjection of them to liquid coagulants, as necessary, to vulcanize or harden them for capacity to withstand tension or strain 15 in their subsequent service as threads. The production of synthetic threads by the old method just briefly outlined, entails the use of complicated and costly apparatus, and requires the maintenance of very exacting operating conditions for predetermination of a product which is 20 uniform in thickness or gauge.

My invention is directed, in the main, toward the provision of an improved method as well as of a simplified apparatus whereby synthetic threads 25 of various cross sectional configurations may be more economically produced in quantity from any of the aforementioned materials, with assurance of absolute regularity as regards uniformity of gauge and quality.

Other objects and attendant advantages will be 30 manifest from the detailed description following in connection with the attached drawing, wherein Fig. I is a longitudinal sectional view showing more or less diagrammatically, a novel apparatus suitable to the practice of my new method of 35 producing elastic threads from aqueous dispersions of latex or rubber or the like.

Fig. II is a detail plan view on a larger scale showing a circumferentially grooved cylinder and 40 a cooperating doctor roll, which, taken together, constitute the forming means of the apparatus, the cylinder being partly broken out and sectioned to better illustrate the character of its grooves.

Figs. III, IV, V and VI are fragmentary detail 45 views on a larger scale, showing cross sectional profiles of different types of grooves for the cylinder; and

Fig. VII is a view corresponding to Fig. I, showing 50 a modified form of apparatus which is especially suited to the production, in accordance with my invention, of synthetic yarns from cellulose solutions and the like.

With more detailed reference first to Figs. I and II of these illustrations, the numeral 1 comprehensively designates the forming cylinder 55

which has been referred to above. As shown, this forming cylinder 1 is of hollow construction and adapted to be heated, for example, by continuous circulation of steam or other fluent heating medium through it, and provided, as shown in Fig. II, with a series of laterally spaced circumferential grooves 8 of square cross sectional configuration. In practice, the cylinder 1 is suitably journaled for rotation in fixed bearings (not shown) and constantly driven in the direction of the arrow in Fig. I, its lower portion dipping into a receptacle 9 containing an aqueous dispersion S of latex or rubber from which the synthetic threads are to be produced. Running in circumferential pressure contact with the forming cylinder 1 and rotating in the same direction, is a doctor roll 10; and overlying a portion of the circumference of the cylinder at the top is a coagulating chamber 11 which is internally heated. Incident to rotation of the forming cylinder 1 in the receptacle 9, its grooves are filled with the solution S, any excess of the latter carried on the surface of said cylinder, being removed by action of the doctor roll 10 and dropping back into the receptacle. If found desirable or convenient in practice a scraper or doctor blade may be used in lieu of the doctor roll 10 herein illustrated. After passing through the coagulating chamber 11, the strands of the material filling within the grooves of the forming cylinder 1 are set or hardened to a certain extent and thus rendered sufficiently strong for removal as filaments F by a draw-off roller 12, the setting or hardening being materially promoted by the internal heating of said cylinder. The filaments F are finally passed through a drying and vulcanizing chamber 13 to which they are directed, after leaving the draw-off roller 12, by a guide roller 14. In traversing the drying and vulcanizing chamber 13, the filaments F are supported against sagging by a series of rollers 15; and, upon emerging from said chamber said filaments are collected as finished threads on a spool or beam 16. The rollers 12, 15 and the collecting beam 16 may be driven, by any suitable drive means, at a surface speed synchronous with that of the forming cylinder 1 to avoid stretching of the filaments; or they may be differentially driven in respect to said forming cylinder to determine a definite attenuation of the filaments. In either case, the square cross sectional configuration determined by the grooves 8 of the cylinder 1 will persist in the finished threads.

When threads of triangular cross section are desired, the forming cylinder is provided with 55

circumferential grooves having the profile shown at 8a, in Fig. III and at 8b in Fig. VI.

Grooves of an arcuate profile, such as shown at 8c in Fig. IV, will, on the other hand, determine threads of semicircular cross section.

Again, grooves profiled after the manner illustrated at 8d in Fig. V, will predetermine threads of semi-hexagonal cross section.

The above modifications are to be regarded as typical of other profile shapes which may be given the grooves of the forming cylinder in accordance with the cross-sectional configuration desired in the finished threads.

For the purpose of producing rayon from cellulose solutions, my improved apparatus may take the form illustrated in Fig. VII, where, in addition to, or in lieu of a coagulating chamber, there is provided a receptacle 17 for a suitable coagulating solution S'', said receptacle being supported at a level well above the receptacle 9' containing the cellulose solution S'. Dipping into the coagulating solution S'' in the receptacle 17 is a driven feed roller 18 which serves a contacting applicator roll 19 whereby the coagulating solution is applied to the strands of the cellulose occupying the grooves of the forming cylinder 1' above the doctor roll 10'. A scraper blade 20 insures even distribution of the coagulant upon the feed roller 18 and in turn, the application of a prescribed regulated amount of said solution to the cellulose strands. After being set by the coagulant, the cellulose strands are drawn from the forming cylinder as filaments F' for conduction to a chamber, such as shown at 13 in Fig. I, for drying.

From the foregoing it will be evident that I have provided a very simple method and apparatus whereby synthetic threads of any required cross section may be continuously and expeditiously produced.

Having thus described my invention, I claim:

1. The continuous method of producing synthetic threads which comprises running a cylinder partly submerged in a viscous solution or emulsion so that circumferential forming grooves of said cylinder become filled with the fluid; coagulating the solution or emulsion carried up in the forming grooves of the cylinder solely by adhesion with the groove surfaces; and removing the resulting threads from the cylinder grooves.

2. The continuous method of producing elastic threads which comprises running a cylinder partly submerged in an aqueous dispersion of

rubber or latex so that circumferential forming grooves of said cylinder become filled with the fluid; coagulating the fluid carried up in the forming grooves by the cylinder solely by adhesion with the groove surfaces; removing the resulting threads from the cylinder grooves; and thereupon vulcanizing the threads.

3. The method of continuously producing synthetic threads which comprises running a cylinder partly submerged in a viscous solution or emulsion so that circumferential forming grooves of said cylinder become filled with the fluid; applying a suitable liquid coagulating agent to the solution carried up in the forming grooves of the cylinder solely by adhesion with the groove surfaces; and removing the resulting threads from the cylinder grooves.

4. The continuous method of producing synthetic threads which comprises running a cylinder partly submerged in a viscous solution or emulsion so that the circumferential forming grooves of said cylinder become filled with the fluid, carrying the solution or emulsion solely by its adhesion with the groove surfaces, forming the threads to the shape of the grooves of the cylinder, coagulating the solution or emulsion in the cylinder grooves; and removing the resulting threads from the cylinder grooves.

5. The continuous method of producing synthetic threads which comprises running a cylinder partly submerged in a dispersion containing rubber so that the circumferential forming grooves of said cylinder become filled with the fluid, carrying the dispersion solely by its adhesion with the groove surfaces, forming the threads to the shape of the grooves of the cylinder, coagulating the solution or emulsion in the cylinder grooves; removing the resulting threads from the cylinder grooves, and thereupon vulcanizing the threads.

6. The continuous method of producing synthetic threads which comprises running a cylinder partly submerged in a viscous solution or emulsion so that the circumferential forming grooves of said cylinder become filled with the fluid, carrying the solution or emulsion solely by its adhesion with the groove surfaces, forming the threads to the shape of the grooves of the cylinder, coagulating the solution or emulsion in the cylinder grooves with a liquid coagulating agent; and removing the resulting threads from the cylinder grooves.

GLEN S. HIERS.
